UNITED STATES PATENT OFFICE.

JOHN H. FORSSBERG, OF STEPHENSON, MICHIGAN.

AUTOMATIC TRAIN-STOP DEVICE.

1,176,357.

Specification of Letters Patent. Patented Mar. 21, 1916.

Application filed May 9, 1914. Serial No. 837,546.

To all whom it may concern:

Be it known that I, JOHN H. FORSSBERG, a citizen of the United States, residing at Stephenson, in the county of Menominee 5 and State of Michigan, have invented certain new and useful Improvements in Automatic Train-Stop Devices, of which the following is a specification.

My invention relates to new and useful 10 improvements in electrically operated locomotive arresters, and it has particular reference to a system embodying sectional ground conductors designed to close a circuit when two cars or engines are in the 15 same block, the circuit when closed operating automatically to actuate suitable mechanism carried upon the respective locomotives within the block to bring the said locomotives to a stand still and in this manner prevent head on collision.

In connection with a system of the above type, the invention aims as its primary object to provide a novel construction, combination and arrangement of parts, details 25 of which will appear in the course of the following description, wherein reference is had to the accompanying drawings forming a part of this specification, like characters of reference designating similar parts 30 throughout the several views, in which:—

Figure 1 is a side elevation of a locomotive, partly broken away illustrating the arrangement of the operating mechanism in connection therewith; Fig. 2 is an enlarged 35 section on the line 2—2 of Fig. 1; Fig. 3 is a top plan view of the device as illustrated in Fig. 2, that part of the boiler shown in Fig. 2 having been removed; Fig. 4 is a section on the line 4—4 of Fig. 3; Fig. 5 is a section on the line 5—5 of Fig. 4; and Fig. 6 is a diagrammatic view illustrating the electrical circuit.

Before proceeding with the description of the drawings, I desire to call particular 45 attention to the fact that while I have evolved my invention with reference to its application in connection with steam locomotives, the same may be readily utilized as a brake means in connection with trolley cars, electric cars, and such like common carriers.

Referring now to the drawings by numerals, 1 designates as an entirety, the locomotive, 2 the steam chest and 3 the steam supply pipe leading thereto. Beneath the boiler of the locomotive 1 a suitable plat-

form 4 is arranged, said platform being held suspended, as illustrated in Fig. 1, through the medium of a plurality of supporting strips 5, attached, as shown, to the boiler 1. Upon the platform of each locomotive, a dynamo 6 is arranged, said dynamo being driven as illustrated to advantage in Figs. 1 and 2 by a chain 7 arranged at one end over a sprocket 8 on the dynamo shaft and at its opposite end over a second sprocket 9 upon the front axle 10 of the locomotive. A motor 11 is also mounted upon said platform 4, the shaft 12 of which, has mounted thereupon, a gear 13, the teeth of the latter meshing into the teeth of a segment 14 mounted upon a shaft 15 extending transversely of or across the platform, said shaft being journaled in certain of the strips 5. Links 16 are fixedly secured to the respective ends of said shaft 15, said links having slots 17 formed in their free ends, within which slots pins 18 of operating rods 19 work. The rods 19 are connected to slide valves 20 operating within suitable casings 21 open to the inlet pipes 3 of the engine cylinders, which arrangement, as will appear hereinafter, providing for a cutting off of the steam supply through movement of valves 20, in the manner best shown in Figs. 4 and 5 of the drawings.

Ground conductors or auxiliary rails 22 extend parallel with the ordinary railway rails designated 23, one rail 22 being disposed adjacent each of the respective railway rails. Said rails 22 are arranged in blocks, preferably as shown in Fig. 6, this arrangement providing, when two locomotives are in the same block, for the operation 95 of the valves 20 and a shutting off of the steam supply to the respective locomotives.

Arms 24 pivoted as at 25 to the under face of platform 4 hang pendently therefrom, the said arms 24 being in circuit with motors 11, conductors 26 being provided therefor. The rails 23 are also in circuit with motors 11, through the medium of conductors 27, axle 10 and wheels 28 upon said axle. Dynamo 6 is in circuit with an arm 29 pivoted as at 30 to hang pendently from the under face of platform 4, a conductor 31 providing for such circuit. Wheels 32 are carried by the respective arms 24 and 29, the wheels being in engagement with the auxiliary rails or ground conductors 22. Dynamo 6 is also in circuit, by means of a

conductor 33, with the axle 10, car wheels 28 and railway rails 23, this arrangement providing for operation as follows: Should locomotives traveling in opposite directions 5 enter the same block, the circuit between the dynamo 6 of one locomotive, and the motor 11 of the other locomotive, is closed, and, as the respective motors of the said two locomotives each operate to turn the shafts 15 carried thereby, it is apparent that the valves 20 of the respective locomotives will be actuated to close the steam supply to the locomotive cylinders and thus prevent continued running of the locomotives. Arm 24 of one 10 locomotive being engageable with rail 22, and arm 29 of the locomotive traveling in the opposite direction being in engagement with the same rail, it is apparent that the electric circuit between the dynamo of one 15 locomotive and the motor of the other locomotive is closed.

From the foregoing, taken in connection with the accompanying drawings it is apparent that the dynamos of the respective 20 locomotives will be recharged through rotation of axle 10; that the operation of the device is positive, certain and automatic, said operation being controlled by the movement of the locomotives acted upon; and 25 that in actual practice, suitable means may be provided and controlled from a point within the locomotive cab, to break the electric circuit, and provide for a return of the valves 20 to their normal position whereby 30 steam inlet pipes 3 of the respective locomotives may be again opened.

In practice, I have found that the form 35 of my invention, illustrated in the drawings and referred to in the above description, as 40 the preferred embodiment, is the most efficient and practical; yet realizing that the conditions concurrent with the adoption of my device will necessarily vary, I desire to emphasize the fact that various minor 45 changes in details of construction, propor-

tion and arrangement of parts may be resorted to, when required, without sacrificing any of the advantages of my invention, as defined in the appended claim.

Having thus fully described my invention, 50 what I claim as new and desire to secure by Letters Patent, is:—

In a railway safety appliance of the character described, the combination with a track and sectional electrical conductors arranged along the same, of vehicles to travel over the track, electrical contact devices carried by each vehicle and engaging said conductors, a valve operable to control movement of each vehicle, a motor mounted on each vehicle, a dynamo mounted on each vehicle, said dynamo being electrically connected with one of said sectional conductors, said motor being electrically connected with the other of said sectional conductors, the motor of one vehicle being engageable with the same electrical conductor as the dynamo of the approaching vehicle upon the movement of the two vehicles onto the same track section defined by the sectional electrical conductors, means electrically connecting the dynamo and the motor of the respective vehicles with the respective track rails to complete the circuit upon movement as aforesaid, a shaft mounted on each vehicle, 75 a segment mounted on each shaft, said segment being driven through the agency of the motor when energized upon the closing of the electrical circuit, means to drive each motor through movement of the vehicle on which it is arranged, and means to control movement of the valve through operation of the shaft.

In testimony whereof I affix my signature in presence of two witnesses.

JOHN H. FORSSBERG.
